AUTOMATIC RAILWAY CROSSING GATE

Alfred E. McLaren, Joplin, Mo.

Application September 14, 1932, Serial No. 633,169

10 Claims. (Cl. 246—128)

This invention relates to automatic railway crossing gates, and more particularly to a gate operating mechanism controlled by trains approaching a grade crossing for operating the gates to lower them upon the approach of the train and to raise them after the train has passed.

An important object of the invention is to provide a novel form of control mechanism for effecting automatic lowering of the gates at a railroad grade crossing upon the approach of a train.

A further object is to provide an apparatus of the character referred to wherein the time of the lowering of the gates is automatically dependent upon the speed of the approaching train whereby the gates will reach lowered position at approximately the same time the train reaches the grade crossing substantially regardless of the speed of the train.

A further object is to provide electrically controlled power mechanism for operating the gates, and wherein a control block is provided adjacent the grade crossing whereby control of the mechanism is effected by the entrance of a train into the block from either direction.

A further object is to provide an apparatus of the character referred to which does not disturb the use of the control block for switching or other purposes, means being provided for so employing the block without needlessly raising and lowering the gates.

A further object is to provide novel power means for moving the gates between vertical and horizontal positions, such means being in the form of sets of axially aligned solenoids adapted to be progressively brought into operation through suitable automatic means for moving the gates between the two positions.

A further object is to provide novel circuits adapted to be energized upon the entrance of a train into the control block and having suitable time controlled means associated therewith whereby the highway gates will be lowered relatively promptly if the train is moving at such a rate as to pass a predetermined distance into the block within a given time after entering it, the time controlled mechanism being such as to prevent operation of the gates by a relatively slow moving train except through additional means arranged to be controlled by a train as it approaches the highway.

Other objects and advantages of the invention will become apparent during the course of the following description.

In the drawings I have shown one embodiment of the invention. In this showing,

Figure 1 is a diagrammatic view showing the electrical system embodied in the invention,

Figure 2 is a side elevation of one of the crossing gates, a portion of the gate being broken away,

Figure 3 is a section taken substantially on line 3—3 of Figure 2, parts being shown in elevation,

Figure 4 is a section taken substantially on line 4—4 of Figure 3, parts being omitted,

Figure 5 is a detail sectional view on line 5—5 of Figure 3,

Figure 6 is a detail sectional view through the time controlled solenoid and associated elements,

Figure 7 is a diagrammatic sectional view illustrating the electrical means and wiring connections therefor employed for raising and lowering the gates.

Referring to Figure 1 the numeral 10 designates the rails of a railroad over which passes a highway diagrammatically illustrated as at 11. One rail is provided with a section 12 insulated as at 13 from the adjacent portions of the corresponding rail, and the section 12 is of substantial length. In practice, it has been found advisable to extend the rail for a distance of substantially one thousand feet to each side of the center of the highway, thus making the rail section 12 approximately two thousand feet long and electrically connected from end to end.

The other rail is provided with a pair of sections 14 having their adjacent ends arranged substantially centrally of the highway and insulated from each other as at 15. The remote ends of the sections 14 are insulated from the adjacent corresponding rails as at 16. Each of the rail sections 14 is preferably approximately one thousand feet in length and accordingly the remote ends of the sections 14 lie opposite the ends of the section 12. The rail sections 12 and 14 accordingly constitute a control block to be referred to in detail later.

Referring to Figure 1 the numeral 17 designates a source of current having one terminal grounded as at 18 and the opposite terminal connected to the rail section 12 by a wire 19. The passage of the train over the rails 12 and 14 is adapted to close certain circuits to be referred to by electrically connecting the rails 12 and 14 through the wheels and axles of the train.

A pair of magnets 20 and 21 is supported at any suitable point and have coils grounded at one

end respectively as at 22 and 23. The other terminal of the coil 20 is connected by a wire 24 to a contact 26. The other terminal of the coil 21 is connected to one end of a wire 28 to be referred to in detail later, and a wire 29 is connected from the wire 28 to a contact 30 similar to the contact 26. The contacts 26 and 30 are carried by the ends of a lever 31 pivotally supported intermediate its ends as at 32. The lever 31 may be formed of insulating material, or the contacts 26 and 30 may be insulated therefrom.

The wire 27 has one end connected to one of the rail sections 14 and the other end of the wire is connected to a contact 33, carried by a bar 34 preferably formed of insulating material. Springs 35 normally urge the bar 34 upwardly to hold the contact 33 in engagement with a contact 36 acting as a stop to limit the upward movement of the bar 34.

20 The bar 34 is provided at opposite ends with contacts 37 and 38 engageable under certain conditions with the contacts 26 and 30 respectively. The contact 37 is connected to the wire 27 by a lead wire 39, while the contact 38 is connected by a wire 40 to a junction box 41. The bar 34 is provided with armatures 42 for the respective magnets 20 and 21.

30 A second assembly of magnets similar to the magnets 20 and 21 and their associated elements also is employed. Referring to Figure 1, the numerals 42 and 43 designate a pair of magnets having their respective coils grounded at one end as at 44 and 45. A lever 46 is pivotally supported intermediate its ends as at 47 to one side of the coils 42 and 43 and carries contacts 48 and 49 at its ends. The lever 46 is similar to the lever 31 previously described and may be formed of insulating material.

40 The other terminal of the magnet 42 is connected by a wire 50 to the contact 36, and the wire 50 has a branch 51 leading to the contact 48. The second terminal of the magnet 43 is connected by a wire 52 to the contact 49. The contacts 48 and 49 are respectively engageable with contacts 53 and 54 carried by the ends of a bar 55 formed of insulating material. This bar carries armatures 56 and 57 for the respective magnets 42 and 43, and a contact 58 is carried by the bar 55 centrally thereof for engagement with a contact 59. Springs 60 urge the bar 55 upwardly under normal conditions to hold the contact 58 in engagement with the contact 59, and the latter contact acts as a stop to limit the upward movement of the bar 55.

50 The contact 53 of the bar 55 is connected by a wire 61 to the junction box 41. The wire 28, previously described, leads to the stop contact 59. The contact 54 of the arm 55 is connected to one end of a wire 62 leading to the right hand rail section 14. A branch wire 63 is connected between the wire 62 and the contact 58.

60 A wire 64 has one end connected to the junction box 41. The other end portion of the wire 64 forms a supply wire for a plurality of contacts arranged between the rails. As shown, contacts 65 and 66 are arranged adjacent the remote ends of the respective rail sections 14, and in practice, the contacts 65 and 66 are arranged approximately one hundred feet from the ends of the control block. The contacts referred to obviously are supplied with current from the wire 64, and such wire also is connected to inner contacts 67 and 68 arranged fairly close to the inner ends of the rail sections 14.

75 The contacts 65 and 66 are engageable by de-

pressible contactors 69 and 70 respectively, and these contactors are operable by the wheels of a train passing thereover. Wires 71 and 72 are connected to the respective contactors 69 and 70 and are joined at the point 73 to supply current under certain conditions to electrical devices to be referred to. The contacts 67 and 68 are engageable with depressible contactors 74 and 75 respectively, operable by the wheels of a train passing thereover. The last named pair of contactors have a connecting wire 76 and a common wire 77 leads from the wire 76 for a purpose to be described.

80 A control magnet indicated by the numeral 78 has one terminal of its coil grounded as at 79. The other terminal of the coil of magnet 78 is provided with two take-off wires one of which indicated by the numeral 80, leads to a stationary post 81. This post constitutes a contact engageable with a second post 82 pivotally connected at its lower end to a base 83. The junction point 73 is connected to the base 83 by a wire 84. The second wire 85 from the last mentioned terminal of the magnet 80 leads to a contact 86. The magnet 78 is provided with an armature 87 carried by a bar 88 formed of conducting material. The lower end of the bar is pivotally supported by a base 89 connected by a wire 90 to the junction box 41. The bar 88 is provided with a spring 91 urging it away from the magnet 78 and its movement is limited by a stop contact 92 connected to one end of a wire 93. The bar 88 is provided with a contact 94 engageable with the contact 86, and is further provided at its upper end with a contact 95 for a purpose to be described.

90 A control solenoid 96 is arranged adjacent the magnet 78 as shown in Figures 1 and 6, and one end of the coil of the solenoid 96 is grounded as at 97. The other terminal of the solenoid coil is connected to the wire 93 previously described. The solenoid 96 is provided with a tubular armature 98, closed at its outer end as shown in Figure 6. At its outer end the armature 98 carries a contact 99 engageable with the contact 95. The armature 98 is provided with a tubular extension 100 projecting completely through the solenoid 96 and connected to one end of a bellows 101 arranged in axial alignment with the solenoid 96. The opposite end of the bellows is supported by a post 102.

100 A spring 103 is arranged in the bellows to urge the tubular member 100 and armature 98 toward the left as viewed in Figure 6, and the flanged end of the tubular member 100 engages the end of the solenoid to limit the movement of the parts referred to. A check valve 104 is connected to the bellows 101 and permits restricted escape of air therefrom. The check valve is operative to substantially prevent the movement of air into the bellows when the latter expands. The rate of discharge of air through the valve 104 is controlled by an adjustable handle 105 which determines the opening movement of the check valve. The escape of air from the bellows also takes place through a valve 106 cooperating with a seat 107 leading into the interior of the armature 98. Any suitable means may be employed for guiding the valve 106, and in the present instance the valve has been shown as being provided with a stem 108 slidable through the armature 98. A spring 109 normally urges the valve 106 toward open position as will be apparent. A valve control plate 110 is carried by the solenoid 96 and projects therefrom. This plate has an inclined face 111 engageable with a roller 112 carried by the upper end of the valve stem 108, and it will be apparent

that the valve progressively opens as the armature 98 moves inwardly.

The armature 98 and the bar 88 normally occupy the positions shown in Figures 1 and 6 with the contacts 95 and 99 out of engagement with each other, and these contacts are engageable under conditions to be referred to for connecting the contact 95 to the wire 77. For this purpose, the contact 99 is provided with a wire 113 leading 10 to the wire 77, and accordingly the contact 95 will be electrically connected to the wire 77 when the contacts 95 and 99 are brought into engagement with each other. The engagement between these contacts is dependent upon energization of the 15 magnet 78 to attract its armature and energization of the magnet 78 is dependent upon the closing of its circuit across the posts 81 and 82. Under some conditions of operation energization of the magnet 78 is prevented, and for this purpose, the armature 98 is provided at its free end with a depending lug 114 engageable with the projecting upper end of the post 82 when the armature 98 is fully retracted. As previously 20 stated, the posts 81 and 82 may electrically engage each other or may be provided with contacts, and in Figure 6 these posts have been illustrated as being provided respectively with contacts 115 and 116 normally held in engagement by a compression spring 117 acting against the 25 post 82.

The wire 77 shown in Figure 1 leads to a junction box 118 having a pair of contacts 119 and 120. The contact 119 is connected to the end of the wire 77, while the contact 120 is connected to 30 one end of a wire 121 leading from the bar 88 or its base 89. Parallel wires 122 and 123 are provided for the purpose of shunting the circuit across the contacts 119 and 120 by either of a plurality of devices to be described.

40 The numeral 124 designates a magnet having one terminal of its coil grounded as at 125. The other terminal of the coil is connected to one end of a wire 126, and this wire leads to a wire 127 extending between the contact 119 and a contact 128. Another contact 129 is arranged opposite the contact 128 and these two contacts are carried by the ends of a lever 130 preferably formed of insulating material and pivotally supported intermediate its ends. A bar 131 carries the armature 132 of the magnet 124 and is urged downwardly by springs 133. Contacts 134 and 135 are carried by the ends of the bar 131, and the contact 134 is connected by a wire 136 to the contact 120.

55 The bar 131 is preferably formed of insulating material and accordingly the contacts 134 and 135 are not electrically connected to each other. A center contact 137 is carried by the bar 131 and the springs 133 normally retain this contact in 60 engagement with a contact 138. A wire 139 leads from the contact 138 to a junction box 140 and is connected to a contact 141 therein. A wire 142 leads from the contact 141 for a purpose to be 65 described. A wire 143 also leads from the contact 129 to the junction box 140 and is connected to the second contact 144 therein. An outlet wire 145 leads from the contact 144 for a purpose to be 70 described. Current for the circuits including the wires just described may be supplied from the source 17 previously described, but is preferably supplied from a source 146 of higher voltage. One terminal of this source is provided with a wire 147 leading to the contact 135, while the 75 other terminal of the source is provided with a

wire 148 for a purpose to be described. A wire 138' connects wire 147 to contact 137.

Current from the source 146 is utilized in a manner to be described to lower gates at the grade crossing, and the closing of circuits for this purpose is dependent upon the closing of a circuit across the contacts 119 and 120. This is accomplished in a manner to be described through the various mechanisms previously referred to, and several auxiliary devices may be separately 10 or severally employed for closing the circuit across the contacts 119 and 120 if desired under certain conditions. Referring to Figure 1, it will be noted that the wires 122 and 123 are connected respectively to the contacts 118 and 119 15 and the latter accordingly will be bridged whenever electrical contact is established across the wires 122 and 123. For example, an ordinary switch 149, such as a knife switch, may be engageable with a contact 150 and the switch and 20 contact are connected respectively to the wires 122 and 123. Alternatively, a push button 151 may be provided for the same purpose, as may a depressor switch 152. If desired a microphone 153 may be provided to bridge across the wires 122 25 and 123, and this microphone may be adjusted so as to be sensitive to the vibrations caused by the blowing of a locomotive whistle.

The crossing gates have been illustrated diagrammatically in Figures 1 and 7 and structurally in Figures 2, 3, 4, 5 and 7. Referring to Figures 2 and 3, the numeral 154 designates a suitable casing in which is arranged the mechanism for operating the gates. The casing 154 rotatably supports a shaft 155 to one end of 30 which is connected any suitable form of gate 156 preferably provided with a counterweight 157. A sleeve 158 rotatably surrounds the shaft 155 within the casing and is provided with a wheel 159 having a groove 160 in its periphery 40 to receive a cable 161. The ends of the cable are connected respectively to armatures 162 and 163 (see Figure 7) and the armatures operate respectively to rotate the wheel 159 and thus 45 operate the gate 156. As shown in Figure 7, the armature 162 is movable through the cores of axially aligned solenoids 164, while the armature 163 is similarly movable through the cores of a plurality of axially aligned solenoids 165. The solenoids 164 are successively energized from 50 the uppermost to the lowermost solenoid to lower the gate 156, while the solenoids 165 are successively energized in a similar manner after the gate has been lowered for returning it to the uppermost position. The control circuits for the 55 two series of solenoids 164 and 165 will be referred to later.

Referring to Figures 3 and 4, the numeral 166 designates a lever connected centrally thereof to the sleeve 158. The ends of this lever are 60 turned outwardly to form ears 167 in which are arranged eye bolts 168. Springs 169 of the tension type are connected at their outer ends to the eyes of the bolts 168 and these springs have their inner ends connected to a pin 170 extending through the shaft 155.

A bracket 171 is arranged within the casing 154 and is provided at its upper end with a series of arcuately arranged contacts 172, suitably insulated from each other and engageable with a 70 contact 173 carried by the lever 166. The arrangement of the contacts 172 is shown diagrammatically in Figure 7. Starting from one end, such as the left hand end shown in Figure 7, the contacts 172 are connected to the successive 75

solenoids 164, starting from the uppermost solenoid, by wires 174. The wires 174, in turn, are successively connected to the solenoids 165, commencing with the lowermost solenoids, by wires 175. Accordingly it will be apparent that the contact 172 at the extreme left side in Figure 7 is connected to the uppermost solenoid 164 and to the lowermost solenoid 165, while the extreme right hand contact 172 is connected to the lowermost solenoid 164 and to the uppermost solenoid 165. The contact 173 has been diagrammatically represented in Figure 7 as an arm movable with the gate 156, and as the gate swings downwardly in the direction of the arrow, it will be apparent that the contact 173 successively engages the contacts 172 until the contact 172 at the extreme right is reached, at which point the gate will be in a horizontal position. During such operation, the successive solenoids 164 starting from the uppermost solenoid, will be energized, and during the return movement of the gate to vertical position the contact 173 will move toward the left and will successively energize the solenoids 165, starting from the uppermost solenoid. The circuits for accomplishing these two results will be referred to in detail later.

While only one of the gates 156 has been described, it will be apparent that gates are provided at each side of the grade crossing, and accordingly two gates have been illustrated in Figure 1, and such gates will be electrically connected to operate simultaneously. Referring to Figure 1, it will be noted that the wire 148 from the source 146 is connected to the shaft of one of the gates 156, and in practice, the wire will be merely grounded on the casing 154. A branch wire 177 leads from the wire 148 to the other gate unit in a similar manner.

Current is supplied to the solenoids 164 and 165 in the manner previously described, and the upper gate unit shown in Figure 1 is provided with return wires 178 and 179 connected to the solenoids of the respective series 164 and 165. The wires 178 are connected to the wire 145 and thus lead to the contact 144. The wires 179 are connected to the wire 142, and thus lead to the contact 140.

The solenoids of the series 164 and 165 of the lower gate unit shown in Figure 1 also are provided with return wires 180 and 181 respectively, and the wires 180 are connected by a wire 182 to the wire 145. The return wires 181 are connected to a common wire 183 which, in turn, is connected to a wire 184 leading to the wire 142. Thus it will be apparent that the corresponding series of solenoids of the two gate units are connected in parallel.

The shaft 155 of each gate unit is provided with a switch arm 185 (see Figures 1 and 3) and this switch arm is operable over a segmental contact 186. When the gate of each unit is in vertical position, the switch arm 185 is out of contact with its associated contact 186, but engages such contact as soon as the gate starts downwardly and remains in engagement therewith until the gate returns to normal vertical position. Each contact 186 is grounded as at 187.

Each gate is preferably provided with a signal light 188 connected to the associated switch arm 185 by a wire 189. A wire 190 connects each light 188 to one post of a bell 191 or other audible signal. The other posts of the audible signals are

connected to one side of the source 17 by wires 192 and 193.

Means are preferably provided for preventing too rapid movement of the gates 156 as they approach their limits of movement. Such means need not be employed, but preferably is used to eliminate any possible damage to the parts. Referring to Figure 5 the numeral 194 designates a pair of dash pot cylinders having pistons 195 therein provided with restricted ports 196 extending therethrough. These pistons are provided with piston rods 197 extending upwardly above the dash pots and having their upper ends slotted as at 198. The shaft 155 of each gate unit is provided with a lever 199 secured thereto and provided at its ends with pins 200 operating in the slots 198. Each dash pot is provided at its lower end with a depending ear 201 through which passes a pivot pin 202 to pivotally connect the dash pots to the casing 154.

The operation of the apparatus is as follows:

Assuming that a train approaches the control block from the left side as viewed in Figure 1, the entrance of the locomotive into the block electrically connects the rail 12 and the adjacent rail 14 through the wheels and axles of the locomotive. Under such conditions, current will flow from the battery 17 through wire 19 and rail 12, through the locomotive to rail 14, through wire 27 and contacts 33 and 36, through wire 50 to magnet 42, and thence back to the source 17 through grounds 44 and 18. Thus the magnet 42 will be energized to attract its armature 56, and the entire bar 55 will be moved downwardly against the tension of the light springs 60 to bring the contacts 53 and 54 into engagement with the respective contacts 48 and 49 of the lever 46. In this connection it will be noted that the lever 46 is pivoted intermediate its ends and accordingly is adapted to swing about its pivot to insure proper engagement between the contacts of the lever and the contacts 53 and 54.

The circuit through the magnet 42 includes the wire 50, as previously stated, and this wire is connected to the branch wire 51 leading to the contact 48. This contact is now in engagement with the contact 53 due to the energization of the magnet 42, and the contact 53 is connected to the junction box 41 which is merely a single common binding post for the various wires leading thereto.

Accordingly current will flow to the junction box 41, and the point 41 is connected through wire 64 to the several track contacts 65, 66, 67 and 68, and depression of any of the switches associated with the track contacts, under such conditions, will close circuits to be referred to later.

The junction point 41 likewise is connected through wire 90 to the base 89 and thus to the bar 88. Accordingly current will flow through wire 90, base 89, bar 88, stop contact 92 and wire 93, and thence through solenoid 96 and back to the source through grounds 97 and 18. Accordingly it will be apparent that the entrance of a train into the block from the left side as viewed in Figure 1 causes immediate energization of the magnet 42 to attract its armature, thus establishing a circuit through solenoid 96. Referring to Figure 6, it will be apparent that when the solenoid 96 is energized, it will attract its armature 98, thus drawing it inwardly. In this connection it will be noted that the tubular member 100 is preferably formed of nonmagnetic material such as brass or the like. This tubular member connects the armature 98 to the bellows 101, and inward movement of the armature 98 thus com-

presses the bellows, and the check valve 104 opens to permit the escape of air therefrom.

When the armature 98 is in its outermost position as shown in Figure 6, the inclined plate 111, 5 operating against the roller 112, holds the valve 106 substantially in closed position thus minimizing the escape of air from the armature 98, tubular member 100 and bellows 101, as the armature moves inwardly. Thus the solenoid 96 is prevented from rapidly operating its armature, and 10 the latter moves inwardly very slowly at the beginning of its movement, but such movement progressively increases during inward movement of 15 the armature since the roller 112 travels upwardly along the inclined plate 111, thus permitting the valve 106 to progressively open.

The operation of the circuits which are controlled by the armature 98 and contact 95 will depend upon the speed with which the train enters 20 and travels through the control block. For example, it is preferred that the solenoid 96 should cause movement of its armature to completely retracted position in approximately four 25 seconds, and if the circuit through the solenoid 96 is not broken during such interval, in a manner to be described, the lug 114 will engage the upper end of the post 82 to move the contact 116 out of engagement with the contact 115, and thus disconnect the posts 81 and 82. In this connection, 30 it will be noted that the circuit through the magnet 78 leading from the contactor 69 adjacent the rails, is in series with the contacts 115 and 116, and accordingly depression of the contactors 69 when the contacts 115 and 116 are 35 separated will prevent energization of the magnet 78. In other words, if it requires the front wheels of the approaching locomotive more than approximately four seconds to travel from the entrance of the block to the contactors 69, the magnet 78 will not be energized, and certain circuits dependent upon this magnet will not be closed.

Assuming however that the train travels into the entrance of the block at a speed which will cause the front wheels of the locomotive to reach 45 the contactor 69 in less than approximately four seconds, a wholly different result will follow. For example, a train traveling at a speed just above thirty miles per hour will reach the contactor 69 approximately two seconds after entering the block. As previously stated, the entrance of the train into the block immediately closes a circuit 50 through magnet 42 to connect the source 17 to the junction point 41, and this point is connected to the track contacts 65 through wire 64. When 55 the train passes over the contactors 69, this member will be brought into engagement with the contact 65, and thus current will flow through wires 71 and 84 to posts 81 and 82, through wire 80, and thence through the magnet 78 back to the 60 source through grounds 79 and 18.

Under such conditions, the energization of the magnet 78 is permitted for the reason that track contactor 69 has been operated within the time limit necessary for the solenoid armature 98 to travel inwardly short of the point where the contacts 115 and 116 will be engaged. When the magnet 78 is thus energized it attracts its armature 81, and the contacts 94 and 96 will be brought into engagement. Under such conditions a holding circuit for the magnet 78 will be established from the junction point 41 through wire 90, base 89, bar 88, contacts 94 and 96, and wire 85, and thence through the magnet 78 to ground 79. The releasing of the contactor 69 after the front 70 wheels of the locomotive pass thereover accord-

ingly will not disturb the circuit through the magnet 78 and this magnet will remain energized until later deenergized under conditions to be referred to.

With the train traveling at approximately 5 thirty miles an hour, which is the condition of operation now under consideration, it will be apparent that the armature 98 will have traveled inwardly through approximately half of its stroke between the time the locomotive enters the control block and operates the contactor 69. When the magnet 78 attracts its armature the circuit through the solenoid 96 will be broken since the bar 88 will be disconnected from the stop contact 92, and accordingly the spring 103 will start 10 to move the armature 98 back to normal position. It requires approximately four seconds for the armature 98 to travel inwardly to its inner limit of movement, and the check valve 104 is so adjusted as to cause the spring 103 to return the 15 armature 98 to normal position at a slower rate. In practice, it is preferred that the check valve 104 be so adjusted as to permit return movement of the armature to normal position in twenty- 20 six seconds.

Under the conditions of operation referred to, the armature 98 will have traveled inwardly to such a position that it will require eight seconds for its return movement and when the normal position is reached, the gates will start downwardly in a manner to be referred to. Under such conditions, therefore, the train will have 25 traveled into the block approximately half way to the intersection and approximately ten seconds has been required for the train to move 30 such distance. The gates require approximately ten seconds to reach horizontal position, and since it will require another ten seconds for the train to reach the intersection, after the armature 98 has reached normal position, it will be 35 apparent that the gates will reach horizontal position substantially at the time the train reaches the intersection.

Under the conditions previously considered, the energization of the magnet 78 will have attracted 45 its armature 81, and accordingly when the solenoid armature 98 reaches normal position, engagement will be established between contacts 95 and 99. Thus current will flow from the junction point 41 through wire 90, base 89 and bar 50 88, and then across contacts 95 and 99, through wires 113 and 17 to junction post 119. From this point the current flows through wires 127 and 126, and thence through magnet 124 and back to the source through ground 125. This 55 action obviously energizes the magnet 124 and attracts its armature 132, thus bringing the contacts 134 and 135 into engagement with the respective contacts 128 and 129 of the lever 130. This lever is pivoted to permit it to compensate 60 for any inequalities in the movement of the bar 131 whereby proper electrical engagement will be established between the contacts referred to.

Upon energization of the magnet 124, current will flow from the source 149 through wire 147, 65 across contacts 135 and 129, and through wire 143 to the junction post 144. From this point, current flows over wire 145 which is connected to the branch wires 178 leading to the series of solenoids 164, and the current also flows from wire 70 145 through wire 182 to the branch wires of the other series of solenoids 164.

The switch arms 173 of the two gate units will be in engagement with the contacts 172 leading to the uppermost solenoids 164, and under the 75

circumstances a circuit will be completed through the uppermost solenoid 164 of each gate unit. The operation of the two gate units is identical and only one need be referred to in detail. Upon energization of the uppermost solenoid 164 the armature 162 will start to move downwardly thus transmitting movement to the wheel 159. As such movement is imparted to the shaft 155 and gate 156 in a manner to be referred to, the switch 10 arm 173 will be moved progressively into engagement with the successive contacts 172 leading to the successive solenoid coils 164. This action causes the armature 162 to be moved progressively downwardly until the gate is closed, and when 15 the lower limit of movement of the gate is reached, the switch arm 173 will engage the last contact 172 to the right as viewed in Figure 7, thus maintaining the lowermost solenoid 164 energized to hold the gate in horizontal position.

20 Movement is not directly transmitted from the wheel 159 to the gate shaft 155, but is transmitted resiliently through the springs 169. Referring to Figures 3 and 4, it will be seen that the lever 166 is connected to the wheel 159 through 25 sleeve 158, and as the wheel 159 rotates, the lever 166 moves with the wheel, thus tending to move the spring bolts 168 circumferentially out of alignment with the pin 170. This action transmits a 30 circumferential force to the pin 170 tending to rotate it to return to its normal position with 35 relation to the bolts 168. As the wheel 159 rotates, therefore, the shaft 155 will be rotated simultaneously with the wheel in the absence of any disturbing force.

40 The switch arm 173, while shown diagrammatically in Figure 7 as being movable with the gate 45 156, is movable with the lever 166. On the other hand, the gate 156 is not positively connected to the source of power therefor, but derives its moving force through the springs 169. Accordingly, if movement of the gate is interfered with, no damage will result thereto, and when the gate is released it will immediately seek its proper position with the pin 170 in alignment with the bolts 168.

45 The operation described has assumed the train to be moving toward the east, that is from the left toward the right as viewed in Figure 1, and during the movement of the train from the entrance into the block, to the center thereof adjacent the highway, the coil of the magnet 42 will remain energized in the manner previously stated. When the train passes over the insulation 15 to the right hand or east track section 14, current 50 will flow from rail 12 through the axles and wheels of the locomotive, through wire 62 to contacts 54 and 49, through wire 52, and thence through the coil 43 to ground 45. The previous energization of the magnet 42 has depressed the bar 55 and the contacts 49 and 54 will have remained in engagement throughout the passage of the train over the west rail section 14. The wire 62 also is connected to the contact 58, centrally of the bar 55, but engagement between the contacts 58 and 59 will have been broken due to the previous movement 55 of the bar 55 downwardly.

60 Under the conditions stated, with part of the train on the west rail 14 and part on the east rail 14, both coils 42 and 43 will be energized, and the coil 43 obviously will remain energized until the train leaves the east end of the control block. When the rear end of the train leaves the west block 14, the circuit from the rail 12 to the west rail 14 will be broken, and no current 65 will flow through the coil 42. Since the com-

pletion of the previously described circuit to the junction point 41 is dependent upon contact across the rails at the west end of the block, it will be apparent that the circuit to the junction point will be broken when the train passes completely into the east end of the block. While the magnet 43 will be energized under such circumstances in the manner previously described, it will be apparent that the continued attraction of the armature 57 retains the contact 58 out of engagement with the contact 59, and the only circuit then completed will be the circuit through the magnet 43 which accomplishes no other result than the maintenance of the bar 55 in its lower position.

5 The breaking of the circuit through the wire 21 when the train passes completely into the east end of the block obviously breaks the circuit through the wire 90, and since the holding circuit for the magnet 78 is dependent upon passage of current through the wire 90, bar 88 and contacts 94 and 86, the magnet 78 will be deenergized to return to normal position, and the circuit across contacts 95 and 99 will be broken. Of course, when the train passes completely from the east end of the block, the magnet 43 will be deenergized and the springs 60 will move the bar 55 upwardly to restore the normal condition of the entire apparatus.

10 At this point it may be stated that when the magnet 124 is energized to attract its armature, 30 the contacts 128 and 134 will be brought into engagement, and current will flow through wire 90, base 89, wire 121, contact 120, wire 136 and contacts 134 and 128, and thence through wires 127 and 126 through the coil 124 and back to the 35 source through ground 125. The circuit through the wire 121 thus is in parallel with the circuit through the wire 113, but both circuits will be broken when the train passes from the west end of the block since such action breaks the circuit 40 to the junction point 41, and both of the parallel circuits referred to are dependent on the closing of the circuit through the point 41. The circuit through the wire 121 is important however for a 45 reason to be described.

When the circuit through magnet 124 is broken upon the passage of the train from the west end of the block, the springs 133 return the bar 31 to normal position, thus bringing the contacts 131 and 133 into engagement with each other. Under such conditions, current will flow from source 145 through wires 147 and 138', across contacts 131 and 133, and through wire 139 to the junction box contact 141. From this point, current flows through wire 142 to the branch wires 179 of the 55 upper series of solenoids 165 in Figure 1, and the current also flows through wires 184 and 183 to the branch wires 181 of the series of solenoids 165 of the other gate section. The operation of the gates of the two sections also is identical when the gates are moving upwardly, and accordingly the operation of only one gate section need be referred to. Referring to Figure 7, it will be noted that when the gate 156 is in horizontal position the armature 162 will be in its lowermost position 60 and the armature 163 in its uppermost position. At the same time, the switch arm 173 will be in engagement with the contact 172 furthest to the right, and accordingly the branch wires leading to the solenoids 165 will operate to complete 65 a circuit through the uppermost solenoid, through the contact 172 referred to, through switch arm 173, and thence back to the source through wire 148, in the case of the gate section shown above the rails in Figure 1. It will be noted that the 70

75 rails in Figure 1. It will be noted that the 75

switch arm 173 of the other gate section is connected to the wire 148 through wire 177.

The closing of the circuit through the uppermost solenoid 165 starts the gate section moving upwardly from horizontal position, and the switch arm 173 thus moves into engagement with the successive contacts 172, and thus the armature 163 will continue to move downwardly to rotate the gate in the direction opposite to the direction of the arrow in Figure 7 until the gate section reaches its uppermost limit of movement. It will be apparent that the armature 132 of magnet 124 normally is in its lower position, and accordingly the contacts 131 and 133 are normally in engagement. Under such conditions current flows from the battery 146 in the manner described to the branch wires of the solenoids of the two series 165, and when the gate is in vertical position the proper solenoids 165 will be energized to hold the gates in such position. If the gates are tampered with by unauthorized persons attempting to pull them downwardly, such movement will be taken up by the springs 169, and whenever the gates are released, they will automatically return to their uppermost positions.

As previously stated, it is preferred that means be provided for cushioning the gates as they approach their limits of movement. Referring to Figure 5, it will be noted that the shaft 155 of each gate is provided with one of the levers 199 and associated parts. Assuming that the gate associated with the mechanism shown in Figure 5 is in vertical position and starts downwardly with the shaft 155 rotating in a clockwise direction, the lever 199 will move freely until the pins 200 reach the limits of the slots 198, whereupon movement will be transmitted to the pistons 195. The dash pots 194 contain a fluid such as a light oil, and the movement of the oil past the pistons will be restricted by the openings 196. When the point is reached where movement is transmitted to the pistons 195, the gates will have gathered substantial momentum, but the escapement of the oil through the openings 196 will gradually check the movement of the gates causing them to be traveling slowly when they reach horizontal position.

With the gates in lowermost position the pins 200 will be reversed in position with respect to their slots 198, and accordingly the initial movement of the gate back to vertical position will not be retarded. When the lost motion between the slots 198 and pins 200 is taken up however, the further movement of the gates will be retarded. In connection with the retarding mechanism it will be noted that the dash pots 194 are free to swing about their pivots 202 to alter their positions during the swinging movement of the lever 199.

The operation of the apparatus has been completely described in connection with the movement of a train traveling at a sufficient speed to depress the contactors 69 at the west end of the block before the solenoid 98 breaks the contact between the posts 81 and 82. The conditions of operation thus described are desirable in order that the gates may close at approximately the time the train reaches the crossing, such time being governed by the time element involved in the operation of the armature 98 of the solenoid 96. In other words, the longer the train requires to pass from the entrance of the block to the contactor 69, the longer will be the time required for the solenoid 98 to return to normal position

and enter the closing of the gates. Such operation of course takes place provided the train depresses the contactor 69 before the armature 98 has moved to its inner limit of movement.

A different result is obtained in the case of a very slow moving train, or one which stops within the block before approaching the highway. A slow moving train, such as a freight-train, or one coming to a stop at a station preceding the highway 11, passes over the contactor 69 after the armature 98 has moved the arm 92 to separate the contacts 115 and 116, and thus the operation of the contactors 69 does not lower the gates. If such train comes to a stop, or continues to proceed at a slow rate, it will pass over the contactors 114 at a relatively short distance from the highway. At such time it is, of course, desirable to lower the gates.

As previously described, the entrance of the train into the block establishes a circuit under all conditions as far as the junction point 41. When a slow moving train passes over the contactors 114, when the gates have not been previously lowered, current will flow to the junction point 41 in the manner previously described, thence through wires 64 to contact 67, through the contactor 114 and wires 76 and 77 to the junction contact 119. From this point the circuit will be completed through magnet 124 to lower the gates in the manner previously described. The passage of one pair of wheels or one truck of the train past the contactors 114 to release it will not affect the gates, since the momentary energization of the magnet 124 brings the contacts 123 and 124 into engagement with each other. Under such conditions a holding circuit will be established for the magnet 124 from the junction point 41, through wire 98, base 89 and wire 121 to the junction contact 120. From such point, current flows through wire 136, across contacts 134 and 128, through wires 127 and 126, and thence through magnet 124 to ground 125. Thus the gates will continue to move downwardly, and the holding circuit just described will remain closed as long as the train remains in the control block to establish a circuit to the junction point 41. The passage of the train past the control block releases the circuit to the junction point 41, and thus the magnet 124 will be de-energized to drop its armature and thus establish the circuits necessary for raising the gate.

The operation of the system under various conditions has been described in detail with relation to a train moving through the control block from the west toward the east. The operation of the system when a train is moving from the east toward the west is identical, the actuation of the depressor 70 causing the same result as the actuation of the depressor 69, while the actuation of the depressor 75 by a slow moving train causes an operation identical with that following the actuation of the depressor 114. In this connection it will be noted that the contactors 114 and 115 are both connected to the wire 76, which in turn is connected to the wire 77, and accordingly it will be obvious that each causes the same operation, regardless of the direction from which the train approaches, if previous operation has not taken place through the movement of a relatively rapidly moving train.

The only difference between the operation of the contactors 69 and 70 lies in the fact that whereas the circuit is established by an east bound train to the junction point 41 upon energization of the coil 42, the approach of a train

from the east initially causes operation of the magnet 20. A train approaching from the east connects the rail 12 to the east rail section 14, and thus current will travel from the latter over 5 wires 62 and 63 to contact 58. Since the bar 55 is in normal position under such circumstances, the contact 58 is in engagement with the contact 59, and current thus flows from the latter contact through wire 28 to coil 21 and thence 10 back to the source through ground 23. This action attracts the armature 42 of coil 21, thus bringing the contacts 30 and 38 into engagement, whereupon the circuit to the junction point 41 is established from wire 28 through wire 29, 15 across contacts 30 and 38 and through wire 40. From this point, the operation of the system through magnet 78, solenoid 96, etc., is identical with the operation previously described. The purpose of pivoting the lever 31 is the same as in 20 the case of the lever 46, such pivot means being provided to insure proper contact between the contacts 30 and 38.

The energization of coil 21 obviously also 25 brings the contacts 26 and 37 into engagement with each other, and the passage of the west bound train into engagement with the west rail 14 then causes current to flow through wires 27 and 39, across contacts 37 and 26, and thence through wire 24 and coil 20 to the ground 22. 30 Thus the magnet 20 will be energized to retain its armature 42 and the bar 34 in lower position to hold the circuit across the contacts 33 and 35 open and prevent the completion of a circuit to the point 41 as would occur by the movement of 35 an east bound train. Accordingly the gates will open when a west bound train completely clears the east end of the control block.

From the foregoing description it will be apparent that energization of the magnet 124 is dependent upon closing the circuit across the contacts 119 and 120, provided however that a circuit is established as far as the junction point 41. Under some conditions it is desirable to provide auxiliary means for shunting across the contacts 119 and 120, and such means is provided in the form of the switch 148 and push button 151, while an auxiliary depressor 152 may be employed. If desired, the shunt circuit may be closed through the medium of the microphone 45 153 upon the blowing of the whistle of the locomotive. These auxiliary means for closing the shunt circuit are desirable for use where it is necessary to drop the gates from different points in the block for any reason, or where portions of 50 a block are needed for switching cars. They are unnecessary however to the normal operation of the system described.

Audible and visible signals may be used in connection with the movement of the gates, and such signals have been illustrated. In this connection, attention is invited to the fact that the timing mechanism for operating the gates upon actuation of either of the contactors 69 or 70, depending upon the direction of approach of the train, causes the gate to be lowered preferably 60 in ten seconds, and the gate preferably reaches its lowermost or horizontal position at the instant the train reaches the intersection. Accordingly the movement of the gate itself is a signal to approaching persons or vehicles that a train is approaching but it is preferred that additional signals be employed as stated.

Referring to Figure 1 it will be noted that each gate unit is provided with a light signal 188 and 70 an audible signal 191, preferably in the form of

a bell. The switch arm 185 rotates with the gate shaft of each gate unit, and is normally out of engagement with its segmental contact 186. Upon initial movement of the gate downwardly from vertical position, the arm 185 comes into engagement with the contact 186. Under such conditions, current flows from the source 17 through wire 193 to the signal 191 of the upper gate unit in Figure 1, and the branch wire 192 leads to the signal 191 of the other gate unit. 10 The signal circuits are otherwise the same and only one need be described. For example, from the upper signal 191 in Figure 1 current flows through wire 190, through the light 188 and wire 189 to the switch arm 185, thence to the contact 186 and back to the source through ground 187. The contact 186 is preferably of such length that it will be engaged by the arm 185 throughout the movement of the gate, and thus it will be apparent that the signals 188 and 191 will operate immediately after the gate starts its downward movement, and will continue to operate as long as the gate is down, and until it again returns to its normal vertical position. 15

From the foregoing it will be apparent that the present apparatus provides a fully automatic system for operating railway crossing gates, and that the system automatically takes into account the speed of an approaching train, and accordingly the gates are lowered at the proper time, 30 and are never lowered an unnecessarily long time before the train crosses the intersection. If the contactors 69 and 70 were operative for closing circuits to operate the gates immediately upon the approach of a train, the gates would have to 35 be timed to close with respect to the fast moving train, and thus would close entirely too soon for slow moving trains, as previously stated. Moreover, the present system eliminates the operation of the gates in the case of a train entering 40 the block and stopping before it reaches the intersection. The auxiliary shunt circuit closing devices 149, 151, 152 and 153 are for optional use to supplement the normal operation of the system where local or special conditions make such operation desirable. 45

The system also provides safety features in the operation of the gates. For example, if a gate should be pulled down across the highway while no train is passing, the gate action would not be disturbed, the long springs 169 permitting the gate to be drawn down without affecting the other parts of the apparatus. The gate would promptly return to normal position as soon as released. Moreover, if a gate should be held down 50 through unauthorized tampering after a train has passed the highway intersection, the gate action would not be injured for the same reason, and the gate would move to inoperative position upon its release. If a vehicle should attempt to 55 pass under the gates as they start down, the gate may come to rest on the top of the vehicle but would cause no damage thereto due to the action of the springs 169. After passage of the train, the gate would be picked up from such intermediate 60 position on top of the vehicle and would return to normal position. No weight except the pull of the springs 169 would rest on the top of the vehicle since the gate is counterbalanced, and no damage would result to the vehicle. In this 65 connection attention is invited to the fact that the gates move downwardly approximately 45° fairly rapidly and are then checked by the dash pots, and the gates accordingly are prevented from moving at such rate as they approach op- 70 75

erative position as would cause injury to persons or vehicles.

It is to be understood that the form of my invention herewith shown and described is to be taken as a preferred example of the same and that various changes in the shape, size, and arrangement of parts may be resorted to without departing from the spirit of the invention or the scope of the subjoined claims.

10. I claim:

1. Apparatus of the character described comprising a gate for a railway grade crossing, means for operating said gate to move it between vertical inoperative position and horizontal operative position, said operating means comprising a gate lowering solenoid device and a gate raising solenoid device each having a circuit therefor, a switch normally closing the circuit through the second named solenoid device and movable to operative position for closing the circuit through the first named solenoid device, an operating magnet for said switch energizable to move said switch to operative position, and control means for said operating magnet comprising a solenoid energizable by a train passing a predetermined point in advance of the grade crossing, an armature for said solenoid having means for retarding its movement upon energization of the solenoid, said armature also having means tending to urge it to normal position upon deenergization of said solenoid to close a circuit through said operating magnet, and a track device arranged between the grade crossing and said predetermined point and operative by a train passing thereover for deenergizing said solenoid.

2. Apparatus constructed in accordance with claim 1 provided with means operative a predetermined time after initial energization of said solenoid for preventing energization of said operating magnet if more than a predetermined time is required for the train to pass from said predetermined point to said track device.

3. Apparatus constructed in accordance with claim 1 wherein the circuit of said solenoid includes a control magnet having an armature normally occupying a position to close a circuit through said solenoid upon the passage of a train past said predetermined point, the circuit of said control magnet being adapted to be closed upon actuation of said track device and including a switch operative to be opened by the armature of said solenoid if said control magnet is not energized by actuation of the track device within a predetermined time after the passage of a train past said predetermined point.

4. Apparatus of the character described comprising a gate for a railway grade crossing, a pair of electromagnetic devices one of which is operable for moving the gate downwardly to operative position and the other of which is operable for moving the gate upwardly to inoperative position, a circuit for each of said electro-magnetic devices including a switch normally in a position energizing said second named electro-magnetic device, a magnet for moving said switch to an operative position for closing a circuit through the first named electro-magnetic device, a solenoid energizable when a train approaches the grade crossing and reaches a point located a predetermined distance therefrom, an armature for said solenoid, a bellows having one end stationary and the other end connected to said solenoid, means associated with said bellows for restricting the movement of air into and out of the bellows to retard movement of said armature, means

tending to move said armature to a normal position outwardly of said solenoid, means operative when the train has traveled a predetermined distance after energizing said solenoid for breaking the circuit therethrough, and means for energizing said magnet to move said switch to operative position after the armature of said solenoid has returned to normal position.

5. Apparatus constructed in accordance with claim 4 provided with means operative for preventing the breaking of the circuit through said solenoid if the approaching train requires more than a predetermined length of time for reaching the solenoid circuit breaking means.

6. Apparatus of the character described comprising a gate for a railway grade crossing, a pair of electro-magnetic devices one of which is operable for moving the gate downwardly to operative position and the other of which is operable for moving the gate upwardly to inoperative position, a circuit for each of said electro-magnetic devices including a switch normally in a position energizing said second named electro-magnetic device, said switch being movable to an operative position for closing a circuit through the first named electro-magnetic device, a solenoid energizable when a train approaches the grade crossing and reaches a point located a predetermined distance therefrom, an armature for said solenoid, means for retarding the movement of said armature, resilient means tending to urge said armature to a normal position outwardly of said solenoid, trackway means located between said predetermined point and the grade crossing and operable by a train passing thereover for breaking the circuit through said solenoid provided the train moves from said predetermined point to said trackway device within a predetermined minimum time, means for preventing the opening of the solenoid circuit by said trackway device after said solenoid has been energized a predetermined length of time, means operative by said armature when it returns to normal position after having been energized for moving said switch to operative position, and trackway means located near the grade crossing for moving said switch to operative position upon the passage of a train thereover if said switch has not been previously moved to such position.

7. Apparatus of the character described comprising, a gate for a railway grade crossing movable downwardly to horizontal operative position and upwardly to vertical inoperative position, a pair of series of superimposed axially aligned solenoids, an armature for each series of solenoids connected to the gate to transmit movement thereto, a switch operative by the gate, a series of contacts engageable by the switch, the contacts of said series starting from one end thereof being connected to the successive solenoids of one series starting from one end thereof and to the solenoids of the other series starting from the other end thereof, a feed wire for each series of solenoids, a source of current, a switch normally connecting the source of current to the feed wire leading to one series of solenoids, said second named switch being movable to an operative position to complete a circuit including said source and the feed wire leading to the other series of solenoids, train operated means including a trackway device located in advance of the grade crossing and operative by a train passing thereover from a predetermined point in advance thereof within a

- predetermined length of time for moving said second named switch to operative position, and trackway means for effecting movement of said second named switch to operative position if said 5 trackway device is not actuated within said predetermined length of time, said trackway means being located between the grade crossing and said trackway device.
8. Apparatus of the character described comprising a railway block extending substantially equidistantly on opposite sides of a grade crossing and insulated from the rails extending beyond the ends thereof, a gate for the grade crossing, power means connected to the gate to move 10 it downwardly to a horizontal operative position and upwardly to a vertical inoperative position, control means for said power means including a trackway device located a predetermined distance from each end of the block, a solenoid energizable upon the entrance of a train into the block and including an armature, means for retarding movement of said armature, spring means tending to return said armature to operative position outwardly of said solenoid, means 15 operative upon actuation of said trackway device for deenergizing said solenoid, a circuit adapted to be closed upon the return of said armature to normal position after said solenoid has been deenergized for rendering the power means operative 20 for lowering the gate, means for rendering each trackway device inoperative for opening the circuit through said solenoid if an approaching train requires more than a predetermined length of time after entering the block for reaching one 25 of said trackway devices, and trackway means arranged between the grade crossing and each of said trackway devices for rendering the power means operative for moving the gate to operative position if said power means has not been 30 previously rendered operative by the train passing over one of said trackway devices.
9. In a gate operating mechanism for railway grade crossings, a rail block forming a part of the railway and extending from the crossing in the 35 direction of train approach, a gate, means for lowering said gate, a contactor arranged intermediate the ends of the rail block, a movable member, means for limiting the speed of movement of said movable member, means urging said movable member in one direction to a normal position, means for initiating and continuing movement of said movable member in the other direction upon and after the entrance of a train into said block, means operative by a train passing over said contactor for releasing said movable member for movement toward normal position, means for preventing operation of said last 40 named means if the train requires more than a predetermined time interval for passing from the entrance end of the block to said contactor, and means rendered operative by said movable member as it returns to normal position after having been released by operation of said contactor for actuating said gate lowering means.
10. In a gate operating mechanism for railway grade crossings, a rail block forming a part of the railway and extending from the crossing in the 45 direction of train approach, a gate, means for lowering said gate, a contactor arranged intermediate the ends of the rail block, a movable member, means for limiting the speed of movement of said movable member, means urging said movable member in one direction to a normal position, means for initiating and continuing movement of said movable member in the other direction upon and after the entrance of a train into said block, means operative by a train passing over said contactor for releasing said movable member for movement toward normal position, means for preventing operation of said last named means if the train requires more than a predetermined time interval for passing from the entrance end of the block to said contactor, and means rendered operative by said movable member as it returns to normal position after having been released by operation of said contactor for actuating said gate lowering means.

ALFRED E. MCCLAREN.
